UNITED STATES PATENT OFFICE.

LESTER S. KEILHOLTZ, OF DAYTON, OHIO, ASSIGNOR, BY MESNE ASSIGNMENTS, TO
DELCO-LIGHT COMPANY, OF DAYTON, OHIO, A CORPORATION OF DELAWARE.

IGNITION SYSTEM.

Application filed August 10, 1918. Serial No. 249,219.

To all whom it may concern:

Be it known that I, LESTER S. KEILHOLTZ, a citizen of the United States of America, residing at Dayton, county of Montgomery, State of Ohio, have invented certain new and useful Improvements in Ignition Systems, of which the following is a full, clear, and exact description.

This invention relates to ignition systems for internal-combustion engines and the like, and has among its objects the provision of improvements in the ignition system described and claimed in the copending application of Charles F. Kettering, Serial No. 248,307 filed August 5, 1918.

The invention described in the application referred to provides an ignition system including elements, a certain portion of which may be brought into effect to provide ignition for the engine starting operation, and a certain other portion of which, including certain elements of the first portion of the system, may be brought into effect to provide ignition during the normal running operation of the engine. The said invention includes a manually operated device for rendering the first portion inoperative and the second portion operative, or vice versa, as desired.

It is an object of the present invention to provide in substitution for the manually controlled device, means controlled automatically in accordance with the speed of the engine for rendering one portion of the operatively associated devices inoperative, and for rendering the other portion operative, or vice versa, in accordance with the operation of the engine.

Other and further objects of the present invention will be apparent from the following description of a preferred embodiment thereof, reference being made to the accompanying drawings.

In the drawings:

Fig. 1 is a sectional view of the ignition unit shown in Fig. 2, the section being taken on the line 1—1 of Fig. 2; and

Fig. 2 is a front elevation of the ignition unit embodied in the present invention, together with a wiring diagram and a dia-grammatic side elevation of certain parts of an internal combustion engine to which the present invention is applied.

Referring to the drawings, 20 designates the cylinder of an internal-combustion en-

gine, in which reciprocates a piston 21, connected by means of the connecting rod 22 to a crank pin 23 carried by crank shaft 24, which is mounted to rotate in bearings 25 and 26 which are suitably supported upon the engine frame, not shown. A generator armature 30 is mounted on the shaft 24, and cooperates with a generator field, not shown, for generating an electric current which is conducted from the armature windings to a commutator 31, or to slip rings 32 and 33. Brushes 34 and 35 cooperate with the slip rings 32 and 33 to conduct current generated in the armature 30 to the primary transformer winding 36. A secondary transformer winding 37 cooperates with winding 36 to transform the current to a voltage suitable for ignition purposes. Transformer winding 37 is connected by wires 38 and 40 with a primary winding 41 of the ignition unit, to be described. Winding 41 is connected by a wire 42 with an ignition timer 43, connected by wire 44 with the transformer winding 37. The circuit just described is a primary circuit of an ignition system using alternating current. It is obvious that current might be supplied directly to this primary circuit from the commutator 31, if the voltage be suitable for ignition purposes. The primary circuit may also be supplied with current from a battery or other external source, but as is apparent, the primary circuit may as well be energized by current supplied by the generator driven by the engine, thus making the use of an external source of current unnecessary. A secondary winding 45, which includes a relatively large number of turns of fine wire surrounds the primary winding 41, and is grounded at 46 and connected by wire 47 to the spark plug 48.

50 designates as a whole, the ignition unit which comprises a supporting frame 51 which may be mounted upon the frame of the engine in any suitable manner. Mounted upon the frame 51 are soft iron cores 53 and 54 upon which are placed the windings 41 and 45, which have been described. 55 and 56 are permanent magnets secured upon the cores 53 and 54 near the upper ends thereof, said magnets 55 and 56 being placed with like poles adjacent. 57 and 58 are soft iron armatures which are slidably mounted on the reduced squared end portions 59 and 60 respectively of bar 61. The distance be-

tween the shoulders 63 and 64 formed on bar 61 by reducing the end portions thereof is less than the length of the cores 53 and 54. Springs 65 and 66 are interposed between the armatures 57 and 58 respectively, and washers 67 and 68, respectively, which are retained by means of pins 69 and 70, respectively, which pass through the bar 61. Said springs 65 and 66 serve to yieldingly maintain the armatures 57 and 58 in engagement with the cores 53 and 54. The bar 61 is mounted to slide in a bearing 71 formed in the bracket 51, and is provided with a dog 72. A reciprocating bar 73 is mounted to slide in the frame 51 and carries at its lower end a roller 74 which cooperates with a cam 96, to be described. Bar 73 carries near its upper end a pivotally mounted latch 77 which is yieldingly urged by spring 78 toward the dog 72. The latch 77 is provided with a ledge 79 which cooperates with the dog 72 in a manner to be described, and said latch 77 is provided with a bevelled surface 80 which cooperates with the bevelled surface 81 formed in the trip member 82. A cover 83 is secured to the frame 51 and serves as a housing for the different parts of the unit.

A cam shaft 90 is mounted in the engine frame, not shown, in any suitable manner and is geared to crank shaft 24 by gears 91 and 92. Shaft 90 extends into the enclosure formed between the frame 51 and the cover 83 and carries the timer cam 98 which controls the opening and closing of timer contacts 94 and 95.

A cam 96 is slidably mounted on shaft 90 and is provided with a cylindrical surface 97 and a camming surface 98, either surface cooperating with roller 74, as will be described. Cam 96 is provided with a collar 99 and a slot 100 through which passes a pin 101 fixed in the shaft 90, which serves as a driving connection between the shaft 90 and the cam 96. A yoke 102 fixed upon shaft 90 carries bell-crank levers 103 and 104 which carry centrifugal weights 105, and are forked so as to engage the collar 99. A spring 106 connecting the levers 103 and 104 yieldingly maintains the said levers in position as shown in Fig. 1.

A washer 107 of insulating material is mounted on cam 96 and is adapted to engage contact 108 of ignition switch 39 and force the same into engagement with contact 109.

The operation of the device is as follows: When the engine is cranked, motion will be transmitted from the crank shaft 24 to the cam 96 through the gearing 92 and 91. The cam being in position as shown in Fig. 1, will rotate and cause the bar 73 to reciprocate in the frame 51. As the bar 73 moves upwardly, as viewed in Fig. 1, the ledge 79 on the latch 77 will engage the dog 72 and

cause the bar 61 to move upwardly. Upward movement of the bar will bring the shoulder 64 into engagement with the armature 58, thus causing the armature 58 to move away from the ends of the cores 53 and 54. During this upward movement of the bar 61 the spring 65 will be compressed and the armature 57 will be firmly held against the lower ends of the cores 53 and 54. Thus a complete metallic magnetic circuit is established through magnets 55 and 56, core 53, armature 57 and core 54.

Further movement of the reciprocating bar 73 will cause the camming surface 80 of the latch 77 to engage the surface 81 of the trip member 82; and as the upward movement of bar 73 continues, the latch 77 will release the dog 72 and will permit the bar 61 to move rapidly downward, by virtue of its own weight and the pressure stored in the spring 65. This downward movement of the bar 61 will bring the armature 58 down into engagement with the cores 53 and 54, and after this engagement has taken place the bar 61 will continue its movement by virtue of the momentum stored in it. The shoulder 63 will engage the armature 57 and cause the movement thereof a short distance away from the lower ends of the cores 53 and 54. When these movements of armatures 58 and 57 take place the magnetic field established through the cores 53 and 54 will be short circuited by the armature 58, and the flux change will occur at a rate such as to create a sparking impulse in the winding 45 of sufficient magnitude to cause a spark to jump in the spark plug 48. A spring 84 which is interposed between the lower end of a slot in bar 73 and the pin 85 mounted in frame 51, causes the bar 73 to turn to its lowest position and to yieldingly maintain the roller 73 in an engagement with the cam 96.

After the engine has become self-operative and has reached a certain speed, the weights 105 will separate sufficiently to cause the movement of cam 96 to the left, as viewed in Fig. 1, and the movement of cam surface 98 cut from under the bar 73, at which time the roller 74 will engage the cylindrical surface 97 and the bar 73 will not be reciprocated. Just before this happens, however, the washer 107 will have been moved into engagement with contact 108, and contact 108 into engagement with contact 109. The timer 43 will then be effective to make and break the primary circuit, described, and to render the coil 41 effective electro-magnetically to create sparking impulses in the winding 45.

It will be apparent from the foregoing description that the reciprocating bar 73 and its associated moving parts provides a mechanical means for intermittently creating and destroying a magnetic field in the

region of the secondary winding or inductive circuit 45, and, likewise, the primary circuit through the timer 43 and the winding 41 provides an electrical means adapted 5 to accomplish the same result. It will be observed further that the mechanical means is rendered inoperative by the mechanical action of the speed-controlled means in arresting the motion of its moving parts, and 10 the electrical means is rendered inoperative by the electrical action of the speed-controlled means in opening its electrical circuit.

An ignition system embodying the present 15 invention possesses the advantages of an impulse generator ignition system for supplying ignition at low engine speed and has the advantages of a silent operating battery-type system without the disadvantage of 20 providing a separate storage battery or other source of current independent of the engine. This invention possesses a further advantage in that the impulse generator feature of the system becomes automatically 25 inoperative after the engine becomes self-operative; and no further act is required to place the battery-type system into operation.

It will be understood that instead of the 30 centrifugal device herein disclosed any electrical or other equivalent means may be employed for moving the cam 96 to the on or off position herein described.

While the form of mechanism herein 35 shown and described constitutes a preferred form of embodiment of the invention, it is to be understood that other forms might be adopted, all coming within the scope of the claims which follow.

40 What I claim is as follows:

1. In combination with an internal-combustion engine, an ignition system comprising an inductive circuit; means providing a magnetic path linked with the circuit; electrical and mechanical means for intermittently creating and destroying a magnetic field in the region of said inductive circuit whereby to induce a sparking impulse therein, said electrical means comprising an electrical circuit and said mechanical means comprising a movable member for continually varying the reluctance of said magnetic path; and means responsive to an operating condition of the engine for rendering 55 either of the first-mentioned means inoperative, said last-mentioned means including provisions for arresting the movement of said movable member.

2. In combination with an internal-combustion engine, an ignition system comprising an inductive circuit; means providing a magnetic path linked with the circuit; electrical and mechanical means for intermittently creating and destroying a magnetic field in the region of said inductive circuit

whereby to induce a sparking impulse therein, said electrical means comprising an electrical circuit and said mechanical means comprising a movable member for continually varying the reluctance of said magnetic path; and means responsive to an operating condition of the engine for rendering either of the first-mentioned means inoperative, said last-mentioned means including provisions for arresting the movement of 70 said movable member and for rendering said electrical circuit inoperative.

3. In combination with an internal-combustion engine, an ignition system comprising an inductive circuit; a source of magnetism; a core cooperating with the inductive circuit for conducting and concentrating magnetism from the said source in the region of said circuit; a second inductive circuit cooperating electro-magnetically with 80 the core and first named inductive circuit; a source of current, and an ignition timer adapted to be connected with the second inductive circuit; means for mechanically short-circuiting the source of magnetism; 85 and means dependent on the operation of the engine, for automatically rendering the short-circuiting means inoperative and for connecting the second named inductive circuit with the timer and current source, 90 whereby a sparking impulse may be created electro-magnetically in the first inductive circuit.

4. In combination with an internal-combustion engine, an ignition system comprising an inductive winding and a permanent magnet; a core cooperating with the winding for conducting and concentrating magnetism from the permanent magnet in the region of the winding; means for short-circuiting the permanent magnet from the core; an ignition timer; a source of current; a second inductive winding arranged to cooperate with the first named inductive winding; and means dependent on the operation 100 of the engine for rendering the short-circuiting means inoperative and for bringing the second named inductive winding into operation whereby to create a sparking impulse 110 in the first named inductive winding. 115

5. In combination with an internal combustion engine, an ignition system comprising an inductive winding; a permanent magnet; cores cooperating therewith and with the winding for conducting magnetism from the permanent magnet to the region of the winding; a movable armature cooperating with the cores for completing the magnetic circuit through the cores; a second movable armature for short-circuiting the magnetism of the permanent magnet away from the cores; a second inductive winding cooperating with the cores of the first inductive winding; an ignition timer; 120 a source of current adapted to be connected 126 to the second inductive winding; and means responsive to an operating condition of the engine for rendering the short-circuiting means inoperative and for bringing the second named inductive winding into operation whereby to create a sparking impulse 130 in the first named inductive winding.

- with the timer and with the second inductive winding; an engine-driven reciprocating member actuating the armatures first to complete the magnetic circuit through the 5 cores and then to short-circuit magnetism away from the cores; and means dependent on the operation of the engine for rendering the reciprocating member inoperative and for connecting the second inductive 10 winding with the timer and source of current whereby a sparking impulse may be created in the first named inductive winding.
6. In combination with an internal-combustion engine, an ignition system comprising a plurality of elements, a certain portion of which may be cooperatively associated to provide ignition to be used before the engine becomes self-operative said portion 15 including means for providing a magnetic path of high permeability and a movable member for continually varying the reluctance thereof, and a certain portion of which may be cooperatively associated to 20 provide suitable ignition for the engine running, said second portion including certain elements of the first portion; and means responsive to an operating condition of the engine for rendering either of said portions 25 operative, said last-mentioned means including provisions for arresting the movement of said movable member.
7. In combination with an internal-combustion engine, an ignition system comprising an inductive circuit; a magnetic path through the circuit; electrical means for intermittently creating and destroying a magnetic field in the region of said circuit, said means including a timer, a source of 30 current and a second inductive circuit; a switch controlling the operation of said elec- 35 trical means; mechanical means for intermittently creating and destroying a magnetic field in the region of said circuit including a permanent magnet and a reciprocating member arranged to cause flux from the magnet to pass intermittently through said magnetic path; an engine driven shaft carrying a cam for operating said timer; a cam for operating said reciprocating member mounted to slide upon said shaft and to be driven thereby; and a centrifugal device carried by said shaft and arranged, when the speed of the engine exceeds a predetermined amount, to move said last mentioned cam out of operative relation with the reciprocating member and into a position for closing said switch whereby to render said electrical means operative and said mechanical means inoperative. 45 50 55 60
8. In combination with an internal-combustion engine; an ignition system therefor comprising an inductive circuit; means comprising a magnet and a movable member for periodically varying the magnetic flux 65 density in the region of the inductive circuit whereby to induce a sparking impulse therein; means comprising a second inductive circuit for also varying the said magnetic flux density; and means responsive to 70 an operating condition of the engine for rendering either of the first mentioned means inoperative; said last-mentioned means including provisions for arresting the movement of said movable member. 75

In testimony whereof I affix my signature.
